UNITED STATES PATENT OFFICE.

WILLIAM H. TAYLOR, OF RICHMOND, VIRGINIA.

CAR-AXLE BOX.

SPECIFICATION forming part of Letters Patent No. 242,715, dated June 7, 1881.

Application filed February 25, 1881. (No model.)

To all whom it may concern:

Be it known that I, WILLIAM H. TAYLOR, of Richmond, in the county of Henrico and State of Virginia, have invented a new Improvement 5 in Car-Axle Boxes, of which the following is a full, clear, and exact description.

The object of my invention is to prevent journals of car-axes from heating, and thus avoid the risk of danger and injury resulting from 10 hot boxes on railroad-trains. For this purpose I provide for retaining water in contact with the box on one or more sides to dissipate the heat arising from friction.

My invention consists in an axle-box formed 15 with water compartments or spaces, as hereinafter described and claimed.

In the accompanying drawings, Figure 1 is a side elevation, partially in section, of a car-axle box embodying my invention; and Fig. 2 20 is a cross-section of the same.

Similar letters of reference indicate corresponding parts.

A is an axle-box, of usual shape, and of ordinary size or larger, as the case may require.

25 B is the axle, a the journal of the axle, and b the bearing-block.

The box A is formed with two vertical partitions, *cc*, which form two tight compartments,

d, for containing water, one at each side of the middle compartment, that contains the block 30 *b* and packing. The water-compartments are accessible from the top, and are preferably left uncovered, so that the water can be poured in from time to time, as required. It will be seen that the water is thus retained in contact with 35 the sides of the journal-compartment, so that in case the journal begins to heat the water will absorb the heat, and so long as there is water in the spaces the journal will be kept comparatively cool. In case of heating on account of there being no water in the box the 40 box will be rapidly cooled by refilling the spaces.

The size, location, and number of the water-spaces may be varied without departing from the scope of my invention.

Having thus described my invention, what I claim as new, and desire to secure by Letters Patent, is—

The axle-box A, formed with partitions *c* between its sides, whereby water-tight spaces *d* 50 are provided at opposite sides of the central oil-space, substantially as shown and described.

WILLIAM HANNIS TAYLOR.
